(57) CLAIM

The ornamental design for a wireless headphone and power bank set, as shown and described.

DESCRIPTION

FIG. 1 is a front perspective view of a wireless headphone and power bank set showing my new design;

FIG. 2 is a front elevational view thereof;

FIG. 3 is a perspective view of the power bank, of the wireless headphone and power bank set showing the new design, shown separately for ease of illustration;

FIG. 4 is rear perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof;

FIG. 11 is a perspective view of wireless headphone, of the wireless headphone and power bank set, shown separately for ease of illustration;

FIG. 12 is a perspective view thereof;

FIG. 13 is a front elevational view thereof;

FIG. 14 is a back elevational view thereof;

FIG. 15 is a left side view thereof;

FIG. 16 is a right side view thereof;

FIG. 17 is a top view thereof; and,

FIG. 18 is a bottom view thereof.

The broken lines shown in the drawings depict portions of the wireless headphone and power bank set that form no part of the claimed design.
